(74) Attorney, Agent, or Firm — ArentFox Schiff LLP

(57) CLAIM

The ornamental design for a garment as shown and described.

DESCRIPTION

FIG. 1 is a front, top, right side perspective view of a first embodiment of a garment showing our new design; FIG. 2 is a front view of the design shown in FIG. 1; FIG. 3 is a rear view of the design shown in FIG. 1; FIG. 4 is a top view of the design shown in FIG. 1; FIG. 5 is a bottom view of the design shown in FIG. 1; FIG. 6 is a front, top, right side perspective view of a second embodiment of a garment showing our new design; FIG. 7 is a front view of the design shown in FIG. 6; FIG. 8 is a rear view of the design shown in FIG. 6; FIG. 9 is a top view of the design shown in FIG. 6; and, FIG. 10 is a bottom view of the design shown in FIG. 6. The dot-dash-dot broken lines in the Figures illustrate portions of the garment that form no part of the claimed design. The broken lines in the Figures illustrate a stitching and form no part of the claimed design.

1 Claim, 10 Drawing Sheets
